UNITED STATES PATENT OFFICE

RUDOLPH SCHILLING, OF WOODSIDE, CALIFORNIA, ASSIGNOR TO HOLZWARTH GAS TURBINE CO., OF SAN FRANCISCO, CALIFORNIA, A CORPORATION OF DELAWARE

COMBUSTION ENGINE

Application filed April 26, 1926. Serial No. 104,553.

My invention relates to combustion engines and more particularly to combustion or explosion turbines. In engines of this class the proper distribution of the explosive mixture and the scavenging of the combustion chamber has presented a problem the solution of which, up to the present time, has been attempted in various ways. It is desirable, in order to secure a maximum of efficiency in the 10 operation of such engines, to insure quick and uniform combustion in the combustion chamber or chambers which form part of the engine. Heretofore attempts have been made to secure this result by constructing the combustion chambers of spherical form, the latter, later on, being changed to a pear-shape with the small end of the chamber directed toward the nozzle valve of the engine; still later on it was found that combustion chambers of cylindrical form and considerable 20 axial length produced the best results but presented difficulties in the proper ignition of the explosive mixture, which difficulties exist to a greater or lesser degree at the present 25 time. The object of the present invention is to provide a novel arrangement whereby these difficulties and other existing disadvantages may be overcome and whereby component parts of the explosive charge may be 30 coincidentally introduced into the combustion chamber at different points therein, the same being true with respect to the introduction of scavenging air and combustion air. Other more specific objects will appear from 35 the description hereinafter and the features of novelty will be pointed out in the claims.

In the accompanying drawing which shows an example of the invention without defining its limits, Fig. 1 is a diagrammatic sectional view illustrating the improvement embodied 40 in a combustion or explosion turbine of the Holzwarth type; and Fig. 2 is a fragmentary similar view illustrating another arrangement of the invention.

45 In the drawing, 5 represents a conventional combustion chamber cylindrical in form and of considerable axial length and of the type generally found in combustion turbines of the Holzwarth type. The combustion chamber 5 is connected with a valve chamber 6 in

which a valve 7 is located, said valve cooperating with a valve seat 8 to control the communication between the combustion chamber 5 and the valve chamber 6. A nozzle 9 leads from the valve chamber and is located in operative relation to the blades of the rotor 10 which is carried by a shaft 11 and rotates in operative relation to the blades of the stator 12. The combustion chamber 5 is provided with a spark plug 13 or equivalent ignition means whereby the explosive charge in the combustion chamber is exploded at the proper time.

In the exemplification of the invention shown in Fig. 1, a plurality of conduits 14 lead from a distributing chamber 15 to the combustion chamber 5 and communicate with the interior thereof at different points spaced apart in the direction of the axis of said chamber 5. In the form shown in Fig. 1, the distributing chamber is located at one end of the combustion chamber 5 and communicates with a valve chamber 16 which, in turn, is connected by means of a pipe 17 or its equivalent, with a source of fuel for introduction 55 into the combustion chamber 5. A suitably operated valve 18 controls the communication between the distributing chamber 15 and the valve chamber 16 and consequently controls the flow of the fuel, or in other words the 60 combustion elements, through the conduits 14.

In the form shown in Fig. 2, the distributing chamber 15a is connected by means of a pipe 17a directly with the source of combustion elements and a controlling valve 18a is located in each one of the conduits 14a which correspond to the conduits 14 of Fig. 1. With the arrangement of Fig. 2, the valves 18a each serve to control the flow of the explosive mixture through the conduits in which the particular valve is located.

It will be understood that the various conduits 14 and 14a may be individually connected with independent sources of fluids if this should be desired. This is illustrated in Fig. 2 wherein a separate chamber 15b, fed by a conduit 17b, is provided. This chamber is connected by a conduit 14b with the combustion chamber, a suitable valve 18b being located in said conduit. With such an ar- 95 100

rangement, it is possible to feed mixtures of different degrees of richness at different portions of the combustion chamber.

In all of the forms of the invention, the conduits 14, 14a, or their equivalent, are arranged in fluid conducting relation to the combustion chamber 5 at different points thereof, and serve to coincidentally conduct component parts of the explosive charge to different points within the combustion chamber 5. In other words, the conduits charge simultaneously similar component parts of the explosive charge; that is, they all charge at the same time either combustion air, or fuel, or a mixture of fuel and air (though the ratios of fuel to air may be different in the mixtures charged by the different conduits), or other operating media such as cooling air or scavenging air. Obviously, the quantity of fluid charged by the different conduits may be different. The conduits or their equivalent likewise are arranged to serve for simultaneously conducting scavenging air or combustion air to different points in said combustion chamber. With the arrangement set forth, the combustion chamber is virtually divided into a plurality of adjacent zones each of which is directly connected with and served by a conduit of its own; as the zones into which the combustion chamber is thus divided represent relatively small parts of the entire volume of said combustion chamber, it is possible to introduce a maximum component part of a complete given charge coincidentally into each of said zones and to thereby quickly and extensively build up a complete charge of maximum explosive and operative efficiency. The same is true if the conduits serve to introduce scavenging air into the combustion chamber from which it follows that the scavenging of the combustion chamber is complete and effective and is carried out in a minimum period of time. The advantages set forth with respect to the introduction of the explosive mixture and scavenging air apply also if the conduits are used for introducing combustion air into the combustion chamber. The operative efficiency of the engine is thereby increased materially, and at the same time, the fuel mixture is utilized for its intended purposes to a maximum degree so that the amount of unburned or unused fuel in each combustion chamber is reduced to a minimum if not entirely obviated. With the arrangement shown in Fig. 2 it is possible also to introduce different kinds of fluids, either fuel or air, or various mixtures thereof, into different parts of the combustion chamber. The improvement does not complicate the construction of the engine or materially increase its cost of production; if desired, the novel features recited herein may be incorporated in existing combustion turbines without any very great difficulty.

It is desirable in turbines of the indicated class to maintain the speed of the jet in the high pressure rotor as well as the exhaust temperature of the combustion gas jet from the nozzle within certain recognized predetermined limits. One method of accomplishing this is to utilize mixtures of low thermal value in the operation of the turbine; such mixtures are however difficult to ignite with spark plugs alone. For this reason it has been the practice to first ignite that portion of the mixture which is located near the customary nozzle valve to thereby create a flame wave which passes backward through the mixture to the usual inlet valve. The present arrangement permits this method to be more efficiently carried out and makes it possible to utilize a mixture of minimum thermal content. This is accomplished by enriching that portion of the mixture in the combustion chamber which is located near the nozzle valve with fuel at the proper moment; such enriching fuel may be readily introduced through the proper conduit 14 or 14a. As a result of such fuel enrichment a ball of fire of great intensity is created which ignites the mixture much more easily than a mere spark, first because the resulting flame spreads over a much greater surface and is much hotter and second, because the major portion of the mixture is compressed by the ball of fire and thereby preheated and made easier to ignite. This is an additional advantage of the improved construction.

The valves may be timed by means of any suitable timing mechanism. Fig. 2 illustrates a satisfactory form of such mechanism, as indicated at 19, the latter being of the pressure-fluid distributor type and adapted to charge periodically a high pressure fluid, such as oil, against the underside of a piston mounted on each valve stem to open the valve, and to cause discharge of such fluid at predetermined instants to permit the valves to close under the action of springs (not shown) or of other pressure means. The distributor may comprise a casing having a hollow revolving member therein rotated by means of a motor 20, said member being adapted to connect periodically, through its interior, the several conduits 21 leading to cylinders in which slide the pistons connected with the valves, with a source of oil under pressure to actuate the pistons to open the valves in timed relation. After the valves have remained open for a predetermined length of time, the communication between the interior of the revolving member, which rotates continuously, and the conduits 21 is interrupted, the pressure oil in the valve cylinders is discharged, and the valves are closed by their springs. The structure and operation of the distributor are described in greater detail in my United States Patent No. 877,194.

Various changes in the specific form shown

and described may be made within the scope of the claims without departing from the spirit of my invention.

I claim:

- 5 1. In a combustion chamber of the intermittent explosion type, an intermittently operated nozzle valve, ignition mechanism for igniting an explosive charge in said chamber, a distributing chamber, a conduit
10 for charging the latter with an operating medium, a plurality of conduits leading from said distributing to said combustion chamber and opening into the latter at a plurality of points, certain of which are spaced in the
15 direction of the longitudinal axis of the chamber, intermittently operated valve mechanism controlling the communication between said charging conduit and said combustion chamber, whereby the same operating medium may
20 be charged intermittently into said chamber at different points therein simultaneously and intimate mixture of the explosion media before ignition promoted, and means for operating said valve and valve mechanism.
- 25 2. The combination set forth in claim 1 wherein said distributing chamber is directly annexed to said combustion chamber.
- 30 3. The combination set forth in claim 1 wherein said distributing chamber is directly annexed to said combustion chamber, and wherein said valve mechanism comprises valves located in said plurality of conduits for regulating the flow of operating medium through said conduits.
- 35 4. The combination set forth in claim 1 wherein said plurality of conduits open into said combustion chamber at a plurality of points all spaced in the direction of the longitudinal axis of the chamber.
- 40 In testimony whereof I have hereunto set my hand.

RUDOLPH SCHILLING.
